GATHERING VALVE FOR PUMPING SYSTEM

Harry E. La Bour, Elkhart, Ind.

Application March 30, 1931, Serial No. 526,195

19 Claims. (Cl. 137—68)

My present invention relates to pumping systems in general and more particularly to valves for use in pumping systems, termed gathering systems, for collecting or gathering liquid from a plurality of locations by means of a single pump.

The invention will be better understood when the purpose is known for which it is provided, and I shall, therefore, briefly review such pumping system above referred to.

Local pockets of water accumulate in mines, excavations, and the like, and a pumping system is provided for their removal. Such system may comprise a pump with several suction openings and suction lines which may be one thousand feet or more long. These suction branches may terminate at different levels so that while one suction line may terminate at a level only a few feet below the pump, others may be located fifteen to twenty feet and more below the pump. The quantity of water flowing into the sumps or pockets is variable and it will be readily seen that the pump will naturally pump from the higher level more rapidly and that as soon as any one sump or pocket is exhausted, air will fill the corresponding suction line with the result that the pumping is stopped from all of the sumps. To prevent this, in previous systems the operators equipped each suction branch with a hand operated valve and had men constantly circulating through the workings to regulate the valves in order to keep the pump in operation.

Many like situations arise where it is desired to gather from different levels, or the same level, liquids as they accumulate in tanks, pockets, sumps or the like. Systems have been proposed heretofore in which automatic valves were provided in the sumps or pockets, but such systems have not been wholly successful, particularly in case of installations in mine service where the water is usually dirty and contains corrosive ingredients, and where from the character of the lifts vacuums of, from twenty-five to twenty-eight inches, often develop under the valve seat. Hence, although much work has been done in the direction of developing an automatic valve controlled by the water level for this service, few, if any satisfactory devices were developed prior to my invention which is disclosed in the Patent No. 1,775,860 of September 16, 1930.

In the above mentioned patent I have shown a system in which a single self-priming pump cooperates with a suction main to which are connected several suction lines each terminating in a gathering valve which may be placed in a sump or pocket. This gathering valve has a large valve

area opening in the direction of suction. This permits the valve to be used as a check-valve and provides ample operating force to open the valve and to hold it open. The valve is connected to a link system which in turn is operable by means of a cam and this cam is in turn operable by a float. This interconnecting mechanism is an inter-lock between the valve and the float. The float prevents the valve from opening until the liquid reaches high level and the valve hinders the float in dropping until the liquid has reached the minimum level. The valve is not closed until the level has lowered to a point where air is drawn into the intake port whereupon the valve is closed and the whole weight of the float may be applied to locking the valve in closed position.

While this entry of air appears to be undesirable and would in conjunction with ordinary centrifugal pumps be likely to cause the pump to become air-bound and to destroy the pump suction, I have shown the valve in my patent referred to coordinated with a self-priming pump which is at all times capable of maintaining its suction even if air is admitted. After the air has once entered the suction pipe through the valve, the valve is closed and before it can again be opened the level of liquid must rise to a predetermined level whereupon the float unlocks the valve and suction opens it. Thus, in the patent mentioned above, I have provided a new and highly advantageous system by coordinating the gathering valve with a self-priming pump capable of pumping air along with liquid. Marginal operation is thereby avoided and wire drawing is prevented.

Further details with reference to the disclosure shown in the Patent 1,775,860, which I have briefly reviewed above, may be had from consulting this patent. I shall now describe my present invention which shows a gathering valve of the character and for the purpose intimated but presenting numerous novel features and advantages over the structure shown in my patent.

The present invention presents, among others, the following novel features:

The individual parts have been appreciably simplified and arranged in cooperative assembly in a novel way with a view to reduce the production costs and to increase the reliability of operation.

I employ a drop valve instead of a lift valve, and the action of this drop valve is assisted by the float.

Several operating parts, such as a counter-weight shown in the structure which is disclosed

in the previously mentioned patent, are eliminated.

The cam operated by the float locks the valve positively in closed position when the float is in its lowest position.

Maximum valve opening with minimum float travel is achieved in a novel manner.

The above and several other features and objects of the present invention will be better understood from a detailed description of the invention which I shall furnish now in order to acquaint those skilled in the art with the manner of constructing and operating my invention. I shall describe the novel structure in connection with the accompanying drawings in which I have shown a specific embodiment of the same.

In the drawings:—

Figure 1 is a vertical longitudinal section through the gathering valve showing the working parts in elevation with the valve in closed position;

Figure 2 is a view similar to Figure 1 but showing the valve in open position;

Figure 3 is a top view of the mechanism with the cover removed; and

Figure 4 is a sectional vertical end view through the casing showing the valve in closed position and certain working parts in elevation and in cross-section respectively.

Like reference numerals denote like parts throughout the several views shown in the drawings.

The valve is contained in a two part housing preferably made of castings. The lower part is substantially rectangular and oblong in shape. It is indicated in the drawings by the reference numeral 1. This lower part of the housing is provided with a flange 2 and with a number of integral mounting brackets such as 3, 4, and 5. The top part 6 of the housing which is of a shape suitable to house the float 7 in a swinging movement, is provided with a companion flange and with laterally projecting flange brackets such as 8, 9 and 10, which register with the mounting brackets 3, 4, 5 on the lower part of the housing when the top part is attached thereto. These flange portions are bolted together by means of bolts such as 11, 12 and 13 for enclosing the mechanism in the housing as shown.

The lower housing section 1 is provided with a number of relatively narrow vertical openings or louvers to permit the entry of water and to exclude coarse material therefrom. These openings are indicated in the drawings by the reference numeral 14. Suitable legs, or bolting flanges may be provided along the sides of the bottom portion 1 so that the housing may be fastened down or otherwise attached to a suitable mounting block or socket, if desired.

The valve mechanism proper comprises several stationary and movable parts. The stationary parts consist of a valve body 15 which is held in place between two flanged casings 16 and 17. The member 15 will be variously referred to as valve plate or valve body and equivalent terms; the chamber defined by the casing 16 will be referred to as suction chamber; and the lower chamber defined by the casing 17 will be termed intake chamber or intake port at various places of the specification. These casings 16 and 17 are bolted together and assembled with the top part 6 of the housing. The upper casing 16 is provided with a threaded portion 18 for the attachment of a threaded end of a suction pipe 75 which may lead to a suction main and the latter

in turn may be in cooperative relation with the pump in a manner generally as described in the Patent 1,775,860, previously referred to. Obviously, bolting flanges may be substituted for the attachment threaded socket portion 18, but I have found the threaded socket more convenient, since it permits the end of the casing 16 to be projected through an opening in the top housing section 6 from the inside thereof, simplifying the assembly greatly.

The inner portion of the valve body 15 forms a valve seat to cooperate with the drop valve 19. This valve body 15 has a central hub or hollow boss 20 in which is guided the stem 21 of the valve 19. The valve stem may be fluted to reduce friction and the likelihood of fouling. The lower end of the valve stem 21 is joined, as indicated at 22, to a pair of short links 23, 23' which are particularly shown in Figure 4. The upper ends of these link members 23 and 23' receive between them the end of the lever 24 and a long pivot pin 25 is passed therethrough. This pivot pin 25 bears at its outer ends, a pair of rollers 26-26'. The other end of the levers 24 is pivotally attached to the support 27 by means of the pin 28. This support 27 may be in the form of a post being formed integral with the valve plate 15 and depending therefrom as particularly shown in the Figures 1 and 2.

The valve casing 16 as well as the valve casing 17 are each provided with laterally projecting flange extensions such as indicated in the drawings by the numerals 30, 31, 32 and 33, 34, 35, respectively. These flange extensions register with each other when the casings 16 and 17 are assembled with the valve plate or body 15 interposed therebetween, as shown. Gaskets such as 36 and 37 are placed between the valve plate 15 and the respective casing members 16 and 17, respectively. The valve casings 16 and 17 with the valve plate 15 interposed are attached as a unit to the upper part 6 of the housing by means of bolts such as 38, 39 and 40 which project through corresponding openings in the flange extensions on the casings, the openings in connection with the upper casing 16 being indicated by the reference numerals 41, 42 and 43, respectively. Special stud bolts such as indicated at 44, 45 and 46 are used for bolting the two casing parts 16 and 17 of the valve body together before attachment of the same in unitary assembly with the cover 6 of the housing. The lower shoulder on each bolt and the lower nuts 48, 50 and 52 hold the flange extensions of the valve body and form the complete bolting means. This assembly of the valve body, with the stud bolts in place is fastened to the upper part 6 of the housing, whereby the upper shoulders on the stud bolts and the upper nuts 47, 49 and 51 form an individual locking scheme.

It is understood, of course, that the above described manner of assembling the two valve casings and of mounting them in unitary assembly with the upper housing may be changed in various ways. For example, plain bolts with threaded ends may be employed and short pieces of tubings may be used for spacing the casing 16 properly relative to the top housing 6.

However, I prefer to employ the first described arrangement. It is more practical and facilitates the assembly of the valve bodies as well as their fastening to the top housing. If the second

- described arrangement were used involving the tubings or spacing sleeves, every time the upper assembly bolts were loosened, the valve body would come apart.
- 5 It will be seen that the valve mechanism as far as the same has been described in the foregoing, shows a drop valve which, by its weight, and by the manner in which it is placed in operative assembly with the valve body has a tendency 10 to remain in closed position. If suction is manifest above the valve, in the chamber defined by the casing 16, this suction will tend to lift the valve from its seat, provided the valve is in a position to be lifted off. This operation depends 15 on the operation of the float 7. Before entering into a discussion how this float operates relative to the valve, I shall describe in the following the manner in which the float is mounted in co-operative relation to the valve.
- 20 The float 7 is mounted on a frame 53 by means of bolts such as 54 and 55. An arm 56 of the frame 53 telescopes into one end 57 of a forked curved lever 58, the end 57 being forked to provide extensions into which the arm 56 of the float frame 53 can telescope, particularly as is shown in Figure 3. The arm 56 of the float is fastened to the forked end 57 of the curved lever 58 by means of bolts such as 59 and 60 which hold the parts in assembly by means of suitable nuts. 25
- 25 The extreme bend of the forked lever 58 is mounted to swing about a pair of pivot pins 61-61 as is particularly indicated in Figure 4. Pivot post or supports such as 62-62 project downwardly from the valve plate 15. These supports 30 may be integral with the valve plate and the curved lever portions 63-63 are disposed between the pivot brackets 62-62 as particularly indicated in Figure 4. The pivot pins 61-61 are driven through the brackets 62-62 to project 35 therefrom and into suitable openings in the arms 63-63 of the curved lever. The lever can therefore swing about these pins 61-61 when the float 7 is moved due to the influx of liquid through the louvers 14 into the valve housing. 40
- 40 Pipe plugs 61'-61' may be mounted in corresponding threaded openings in the wall of the casing 17 in order to secure the pins 61-61 in position and to facilitate assembly and dis-assembly.
- 45 50 The lever 58 which is forked adjacent the pivot ends 61 as described above, comprises cam members such as 65 which extend in the present instance substantially at right angles from the longitudinal portion of the lever. The cam members 65 comprise two different dwells 66 and 67 separated by a relatively sharp knee 68. The two dwells 66 and 67 are distinctive in function. The positive dwell 66 is of such a character as to serve to lock the valve 19 closed. 55
- 55 That is to say, the rise is that of a small angle or thin wedge so that the weight of the float operating through the leverage of the lever 58 is able to hold the valve 19 closed against maximum suction thereon. The negative cam dwell 66 has the function of providing so steep a rise 60 that the impact pressure of liquid flowing against the valve 19 will tend to hold the float 7 in elevated position. The rise of the cam dwell 67 is such as to be reversible. It is so shaped as 65 to give a quick drop after the rollers 26-26' (on which the cam portions of the lever ride) pass the knees 68, thus permitting maximum valve opening with minimum float travel.
- 70 The operation of the valve is as follows:
- 75 Assuming that the parts are in the position

shown in the Figures 1 and 4, and that the pump of the system is being driven so as to hold a vacuum in the suction pipe attached to the upper threaded portion of the valve casing 16. There is, therefore, a vacuum above the valve 19, within the suction chamber defined by the casing 16. The relatively large area of the valve 19 with the difference in pressures which exists thereupon provides a large opening force which, however, is prevented from operating to open the valve 19 due to the fact that the valve 19 is locked in closed position by the dwells 66 which engage the rollers 26 as shown. The dwells 66 are thrust under the rollers 26-26' by the weight of the float 7. The weight of the float operating through the mechanical advantages secured by the levers and the cam dwells 66 is capable of closing and holding closed the valve 19 even against the maximum difference of pressure established by the suction created by the pumping system.

Let us assume now that the liquid level rises in the pocket or sump in which the mechanism is disposed. The liquid will enter into the valve housing through the louvers 14 and will raise the float. The dwells 66-66 of the cams 65-65 will therefore slide to the right (as seen in Figure 1) along the rollers 26-26' to a point where the knees 68 pass the lines of centers between the rollers 26-26' and the pivot points 61 of the cams. At this point of the rise of the float 7 the cam relation is changed. The valve 19 will be unlocked and will begin to open. The rollers 26-26' then operate on cam dwells 67 and since the angle of these cam dwells is such that after the rollers once pass over the knees 68 the flow 30 of liquid will be able to throw the valve wide open and, acting through the rollers, simultaneously raise the float to a small lift above its previous position, that is, above its release position. The float will then occupy the high float position in which it is shown in Figure 2. The valve 19 now takes control of the float. As long as there is suction maintained in the suction chamber above the valve 19, the float will remain in the position in which it is shown in Figure 2 and the valve 40 will remain in wide open position, permitting the pump to draw out the liquid which accumulates in the valve housing, entering into the housing through the louvers 14.

The pump will then continue to draw liquid 50 through the intake port of the valve, holding the port in the open position just described, and the level of the liquid will drop. It may be observed that I have provided in the top of the casing 6 openings such as 70 and 71 to prevent 55 trapping of air or liquid in the dome formed by the top of the cover of the housing.

It shall be assumed now that the level of the liquid drops below the lower margin of the valve casing 17 while the pump continues to operate 60 creating suction above the valve 19. Air will now enter the intake port above the valve 19 and the pressure difference will therefore be reduced. Accordingly, there being insufficient difference in pressure to maintain the mechanism in the position in which it is shown in the drawings, Figure 2, the weight of the float 7 and also the weight of the valve 19 will cause the valve 19 to drop since the pressure difference is not strong enough to hold the valve 7 in the raised position in which it is shown, and in dropping, the mechanism will assume the position in which it is shown in Figure 1. In other words, the valve will be locked in closed position by the locking dwells 66-66 of the cam 65.

It has been assumed in the above description of the operation of the mechanism that the suction created by the pump and effective to the intake port or suction chamber above the valve 19 is strong enough to maintain the valve in the raised position in which it is shown in Figure 2 with the valve 19 wide open.

It will be assumed now that the suction is strong enough to draw liquid but not strong enough to maintain the float in the raised position in which it is shown in Figure 2 with a liquid level only slightly above the lower margin of the opening of the lower casing 17. If this is the case, the float will follow the level of the liquid and partially close the valve until the knees 68 of the cams engage the rollers 26-26'. At this point of the operation the knees of the cam will afford sufficient retarding force to permit the level of the liquid to drop ahead of the float until sufficient differential is secured to permit the weight of the float to snap the cam knees over the rollers 26-26' and to close the valve 19 with a snap action locking the same closed in the position in which it is shown in Figure 1.

In case air should be drawn into the suction pipe in the course of the operation of the valve mechanism as above described, no harm will be done in the system since I employ a self-priming pump as is particularly described in my patent mentioned previously No. 1,775,860.

The closing operation of the valve must be considered in two operations; first, the release of the float which is secured through the passing of the rollers 26-26' to the knees 68 of the cams 65. After the float is released by the passing of the rollers over the cam knees 68 it then brings the valve against its seat even against the force of suction of the pump.

It will be seen now that the valve has a positional control over the float operation and vice versa, the float has a positional control over the valve operation.

As the liquid collects and rises above the low liquid level, it will finally come to a position where it will tend to raise the float. During all this time the valve 19 is shut tight. As the liquid further collects and raises the float the valve 19 may be partially opened and a slight amount of liquid may pass therethrough. Air will not be drawn into the valve intake for if the liquid level should drop below the low float position, the float would thereupon lock the valve completely closed.

It will be observed that when the valve 19 opens it opens suddenly due to the angle of the dwells 67-67' on the cams, thereby tending to clean itself by the sudden inrush of liquid through the port.

Assuming that the pressure exerted by the pump upon the valve 19 is relatively so great as to hold the float in raised position regardless of the liquid level, then the liquid level will fall to such a point that air will be admitted to the valve. This will release a large part of the pressure tending to hold the valve open, with the result that the float will fall suddenly to its lowest position and lock the valve closed. Assuming, however, that the pressure exerted by the pump upon the valve is such that the float follows the liquid level down until the knee of the cam is reached, then the float will be retarded until a sufficient force differential is attained by further drop of the liquid level, whereupon the knees of the cam pass over the rollers, locking the valve closed as previously described. Either of the

above intimated conditions will prevail depending upon the position which the mechanism takes in a pumping system with regard to other like gathering valves.

The principles of my invention may be embodied in a variety of forms and while in the above embodiment I have shown a preferred form, I wish to call attention to the fact that other mechanisms than the specific one which I have shown may be employed.

A comparison of the above described invention with the embodiments shown in the patent previously referred to will reveal the fact that certain features of the present invention exhibit a generally structural and also functional similarity relative to corresponding features shown in the patent. However, such comparison will also reveal the fact that the present embodiment introduces numerous improvements in the structure of details and in their cooperative assembly as well as in their function over the structures described in the prior disclosure. Some of the salient novel features are, for convenience sake, listed below.

In the prior disclosure I have shown a valve body fastened to the valve housing from the side thereof and entering the valve housing, then rising within the valve housing in an angle. The valve mechanism is mounted on this valve body within the housing.

In the present disclosure, the casing enclosing the valve mechanism, projects into the liquid which accumulates, in a manner as if the valve housing were merely a continuation of the suction pipe, dipping directly into the liquid. The valve mechanism is disposed entirely within the valve body instead of being fastened on the same. The valve body is, in other words, constructed so as to function as an extension of the suction pipe which may be assumed to have been dropped into the sump or pocket for removing water from the same.

The advantages secured by this novel arrangement are numerous. The action of the mechanism will be more positive. The removal of liquid from the sump or pocket in which my novel gathering valve is placed will be expedited to the extent of being able to withdraw the water practically down to the ground level of the sump or pocket. The lower casing 17 can of course be extended downwardly if desired. Changes such as a slot in the wall of the casing 17 for the passage of the curved lever are, of course, within the possibilities of my invention.

A further advantage resides in the elimination of certain parts such as a counter weight for securing the action of the valve. I utilize the weight of the valve instead of operating against the force created thereby.

Since the valve body comprising the casings 16 and 17 may be considered as being in the nature of an extension of a suction pipe to be dropped into a sump or water pocket, reaching directly from above into the liquid accumulating in such pocket, there will be no tendency of the liquid to swirl and to set up an air cone. This would be the tendency where the liquid is rapidly withdrawn through a relatively large port opening in a structure in which the valve body is disposed at the bottom of the sump and rises within the liquid in the direction toward the surface level thereof.

Further structural advantages which will be readily appreciated are realized by assembling the valve body and the entire valve and float op-

erating mechanism in a unitary structure with the top part 6 of the housing.

In addition to having eliminated certain details, I have also simplified the operating parts 5 so that production thereof is cheapened. Attention is called, for example, to the simple form of the float which I am able to employ in my novel valve mechanism. The assembly of the parts in operative relation is also rendered simple and therefore cheaper, and maintenance or 10 repair work, should such work be required, will be rendered easier for the same reasons.

As I have intimated previously, the principles of my invention are capable of receiving different structural expressions. I therefore desire to have it expressly understood that I do not intend to be limited to the details shown and described. I have defined in the following claims what I 15 consider new and distinguishing over the art.

20 I claim as my invention:

1. In combination, a valve body comprising a suction chamber, a valve seat and a downwardly opening tubular intake port, a valve cooperating with said valve seat, said valve tending to attach by gravity to said valve seat to seal the passage between said suction chamber and said intake port, a float, and an interlocking connection between said valve and said float and disposed wholly within said tubular intake port.

2. In combination, a valve body comprising a valve seat, a suction chamber disposed above said valve seat, a downwardly opening tubular intake port disposed below said valve seat, means for attaching a suction pipe to said suction chamber, a check valve for said valve seat opening with normal flow and checking upon reverse flow, a float, and a mechanism for maintaining an interlocking connection between said valve and said float, said mechanism being disposed within said intake port for movement therein about an axis above the intake opening.

3. In combination, a valve body comprising a valve seat, a suction chamber disposed above said valve seat, an intake port disposed below said valve seat, a check valve for said valve seat, said valve tending at all times to attach to said valve seat by gravity for sealing the passage between said suction chamber and said intake port, a float, and an interlocking mechanism between said valve and said float and operative to release the valve to permit it to open when the float is in its upper position.

4. In combination, a valve body comprising a valve seat, a suction chamber disposed above said valve seat, an intake port disposed below said valve seat, a check valve for said valve seat, said valve tending at all times to attach to said valve seat for sealing the passage between said suction chamber and said intake port, a float, and an interlocking mechanism between said valve and said float, said interlocking mechanism including cam means operative to hold the valve in closed position when the float is in its lower position disposed within said intake port.

5. In combination, a valve body comprising a valve seat, a suction chamber disposed above said seat, an intake port disposed below said valve seat, a check valve for said valve seat, said valve tending at all times to attach to said valve seat for sealing the passage between said suction chamber and said intake port, a float, and an interlocking mechanism between said valve and said float, said interlocking mechanism being disposed within said intake port and operated by said float upon the attainment of high level liquid to

release said valve and the float thereupon being held in raised position by the valve operating through said interlocking mechanism until the level of liquid is lowered to a predetermined point, the weight of the float being then operative through the interlocking mechanism to lock the valve closed.

6. In combination, a valve body comprising a valve seat, a suction chamber disposed above said valve seat, an intake port disposed below said valve seat, a check valve for said valve seat, said valve tending at all times to attach to said valve seat for sealing the passage between said suction chamber and said intake port, a float, an interlocking mechanism between said valve and said float, a container for housing said float and said valve body with all cooperating parts including said interlocking mechanism and provided with a plurality of inlet openings, a cover for said container, and means for attaching said valve body with all cooperating parts in a unitary assembly to said cover.

7. In combination, a valve body comprising a valve seat, a suction chamber disposed above said valve seat, an intake port disposed below said valve seat, a check valve for said valve seat, a valve tending at all times to attach to said valve seat for sealing the passage between said suction chamber and said intake port, a float, an interlocking mechanism between said valve and said float, said interlocking mechanism being disposed within said intake port and operated by said float upon the attainment of high level of liquid to release said valve, and the float thereupon being held in raised position by the valve operating through the interlocking mechanism until the level of liquid is lowered to a predetermined point, the weight of the float being then operative through the interlocking mechanism to lock the valve closed, a container for housing said float and said valve body with all cooperating parts including said interlocking mechanism, a cover for said container, and means for attaching said valve body with all cooperating parts in a unitary assembly to said cover.

8. In combination, a valve body having an inlet casing, a suction chamber, a plate interposed between said casing and said chamber, a valve seat on said plate, a check valve for said valve seat, a hub on said plate, the stem of said valve extending downwardly through said hub, said check valve opening with normal flow and checking upon reverse flow, a float, and an interlocking connection between said float and said stem, said connection being disposed within said inlet casing.

9. In a liquid gathering system having a downwardly extending suction pipe, a gathering container, a cover for said container, a valve body enclosed within said container, the upper part of said valve body projecting through the cover of said container and having means for attaching said suction pipe thereto, a valve port in said valve body, a check valve for said port opening in the direction of flow produced by suction and closing by the action of the column of liquid in said suction pipe, an intake chamber below said valve port, a float, and irreversible actuating means connecting said float and said valve within said intake chamber to permit said float to move said valve to closed position and to prevent the suction on said valve from actuating said float.

10. In combination, a valve body having a suction chamber, an intake chamber, an inlet port

disposed intermediate of said chambers for permitting the passage of liquid from said intake chamber to said suction chamber, a check valve for said port, a float, means controlled by said float and disposed within said intake chamber for locking said valve in closed position, and means controlled by said valve for holding said float in raised position.

11. In a device of the class described, the assembly of a valve body comprising an intake chamber, a suction chamber, a port opening disposed between said chambers, a check valve for said port, said valve having at all times a tendency to close said port, a float, and means disposed within said intake chamber for connecting said float to said valve, said means serving to hold said float in raised position while said valve is held open by the flow of liquid through said port.

12. In a device of the class described, a tubular valve body having a partition, a port in said partition providing a passage for liquid flow through said valve body, a centrally disposed hub integral with said partition, a valve having a stem engaging said hub, said valve having at all times a tendency to close said port, a float, an interlocking mechanism disposed within said tubular valve body below said valve for connecting said valve stem with said float, means included in said mechanism and operable by said valve for holding said float in raised position during the flow of liquid through said port, and means included in said mechanism and operable by said float for closing said valve and for locking said valve in closed position consequent to the passage of air through said port.

13. In a liquid gathering device of the class described, a tubular valve body, a partition in said body separating said body into a lower intake chamber and an upper suction chamber, means for attaching a suction pipe to said suction chamber, a port in said partition for the passage of liquid from said intake chamber to said suction chamber consequent to the application of suction through said suction pipe, a centrally disposed hub below said port, a valve having a stem engaging said hub and projecting into said intake chamber, said valve having at all times a tendency to close said port, a float, means controlled by said float for locking said valve in closed position consequent to the lowering of the liquid level below the lower edge of said intake chamber, means controlled by said valve for holding said float in raised position during the drawing of liquid through said port, a housing for the device as a unit, a cover for said housing, and means for assembling said mechanism including said valve body, said valve, said float, said locking means, and said holding means in a unitary structure with said cover.

14. A liquid gathering valve device for cooperating with a suction pipe of a pumping system for draining irregularly accumulating liquid from a sump or pocket, comprising a housing, a cover therefor, and a control mechanism in unitary assembly with said cover for permitting the drawing of liquid while preventing the drawing of air through said suction pipe, said mechanism including a tubular body projecting through said cover, means on said tubular body for attaching said suction pipe thereto, a valve seat within said body, a check valve cooperating therewith, a float disposed in said housing, and interlocking means disposed within said tubular body below said

valve seat for holding said float in raised position during the drawing of liquid and for locking said check valve in closed position relative to said valve seat upon lowering of the liquid level to a predetermined position.

15. In combination, a housing, a substantially vertically disposed tubular valve body therein, a suction connection on the upper part of said body, an inlet port facing downwardly and extending to a point adjacent the bottom of the housing and normally adapted to receive liquid, a valve intermediate of said suction connection and said inlet port for closing said inlet port, a float controlled mechanism disposed within said inlet port for controlling said valve, a float arm having a float at one end and a turned up portion at the other end passing under the lower end of said inlet port and extending upwardly to a point therein for attachment to said mechanism, a cover for said housing, and means for attaching said tubular valve body to said cover.

16. A liquid gathering device of the class described, comprising a tubular suction chamber having means at its upper side for connecting a suction pipe thereto, a tubular intake chamber facing downwardly and normally adapted to receive liquid, a plate disposed between said chambers, a valve seat in said plate, a check valve cooperating with said valve seat, said valve having at all times a tendency to attach to said valve seat for preventing the upward passage of liquid from said intake chamber to said suction chamber, a float having an arm extending upwardly into said intake chamber, mechanism disposed within said intake chamber for controlling said valve by means of said float, a housing, a cover therefor, and means for mounting said suction chamber in assembly with said intake chamber and said plate on the inside of said cover.

17. In combination, a valve body having an inlet port, a suction chamber, a plate interposed between said port and said chamber, a valve seat on said plate, a valve for said valve seat, a float and float arm, the latter having a curved portion extending upwardly into the inlet port and fulcrumed on said plate, said curved end terminating in an end disposed below the fulcrum axis and connected with said valve, and means for guiding the valve in its movements relative to said valve seat plate.

18. In combination, a valve body having means forming a pair of serially connected chambers, a plate interposed between said chambers having a valve seat, a valve for the seat adapted to control the fluid flow therethrough, a controlling arm having an end extending generally axially into one of said chambers and pivotally supported from said plate, and operative connections between said end of the arm and said valve.

19. In combination, a valve body having means forming a pair of serially connected chambers, a plate interposed between said chambers having a valve seat, a valve for the seat adapted to control the fluid flow therethrough, a controlling arm having a main portion extending generally at an angle to one of said chambers, a second portion extending generally axially into one of said chambers and pivotally supported from said plate, said second portion disposing the arm to clear the end of the chamber into which the second portion extends, and a third portion operatively connected with the valve to shift the same.
